(57) **CLAIM**

The ornamental design for a housing for arithmetic and control unit, as shown and described.

DESCRIPTION

FIG. 1 is a front elevational view of a housing for arithmetic and control unit showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a left side elevational view wherein the disc tray portion is in the open position. The disc tray portion in broken lines is for illustrative purposes only and forms no part of the claimed design.
